PLASTIC HEAT SEALING MACHINE

Donald L. Wicks, Minneapolis, Minn., assignor, by mesne assignments, to Studebaker Corporation, South Bend, Ind., a corporation of Michigan

Filed May 7, 1962, Ser. No. 70,003

Term of patent 14 years

(Cl. D55—1)

FIGURE 1 is a front perspective view of a plastic heat sealing machine showing my new design;

FIGURE 2 is a top plan view thereof;

FIGURE 3 is a front elevational view thereof;

FIGURE 4 is a fragmentary bottom plan view thereof; and

FIGURE 5 is an end elevational view thereof.

The rear, not shown, is flat and plain as indicated in FIGURES 2, 4, and 5.

I claim:

The ornamental design for a plastic heat sealing machine, substantially as shown and described.
